MANUFACTURE OF FOOTWEAR

Robert H. Fesler, Manhasset, N. Y.

Application May 14, 1943, Serial No. 487,003

11 Claims. (Cl. 36—22)

This invention pertains to the manufacture of footwear and relates more particularly to a novel insole for Goodyear welt-type shoes and to a novel method of making such insoles.

The customary Goodyear welt insole is of substantial thickness and too stiff to permit its margin as a whole to be bent out of the plane of its central portion to receive attaching stitches (as is customary in making shoes of the force-lasted type wherein the insole or sock lining is a thin flexible piece of textile fabric) and thus the Goodyear welt insole is provided with a marginal sewing rib at its underside designed to receive the inseam stitches which unite the welt and upper to the insole. This sewing rib, whether reinforced or not, usually comprises two thin flaps integral with the body of the insole and which are turned up and cemented together thus providing two thicknesses of the insole material to receive the sewing stitches. The inner one of these flaps results from a channeling operation, while the other flap is produced by making an incision in the edge of the sole, in a plane parallel to the bottom of the sole, and turning down the material intervening between the incision and the under surface of the sole to form the second flap. Usually this incision is located nearer to the under or flesh surface of the insole than to the upper or grain surface. The relatively thick and stiff marginal portion of the sole at its grain side projects outwardly beyond the turned-down flap and is called the "feather." Since the outer edge of this feather is spaced (by the width of the down-turned flap) from the outer surface of the sewing rib, the upper must make a sharp, nearly right angular bend in passing from its attachment to the rib upwardly about the edge of the insole. As a result the feather is stressed and tends to bend upwardly during use, thus allowing the upper to become slack and impairing the fit of the shoe. Moreover, such an upward bending of the margin or feather of the insole makes the surface on which the foot rests uneven, the border of this supporting surface being higher than its central portion, and as this upturned border is usually uneven and sometimes undulating or wrinkled, real discomfort may thus be occasioned. At best, the material of the insole which is customarily incorporated in the sewing rib is weak and easily torn, being thin and comprising the flesh side of the leather, and in the cheaper grades and in the thinner insoles the sewing rib, unless reinforced with canvas or the like, is wholly inadequate as an anchorage for the sewing stitches.

In accordance with the present invention the above difficulties are overcome in a very simple and effective way and without undue increase in cost—the improved insole (which in other particulars is a typical Goodyear welt insole of substantial thickness and inherent stiffness) having a sewing rib which comprises three thicknesses of the material of the insole, one of them being from the grain side of the sole, the feather, as such, being entirely eliminated, so that the upper extends upwardly from its anchorage to the rib with but little change in direction. Moreover, the edge of the sole which the upper engages is smoothly rounded and firm so that it does not bend upwardly to any substantial extent during use, thus insuring a smooth and even surface as a support for the foot and maintaining the upper in its lasted shape without substantial yielding or the formation of slack in the upper during use. In accomplishing this desired result the insole is prepared in substantially the usual manner as a preliminary step in the operation, and then, either before or after the application of the canvas reinforcement if such be employed, the feather is reduced in thickness by removing from its flesh side a shaving or skiving of the desired thickness, leaving at the grain side a feather of substantial flexibility. This reduction in thickness of the feather may extend all of the way around the sole from the heel portion at one side to the heel portion at the other side, although under most circumstances it is sufficient and in some cases preferably to leave the feather of normal thickness in the shank portions of the insole and reduce it only at the forepart and toe. After the feather has thus been reduced, the remaining, grain portion of the feather is turned down and cemented to the previously formed rib, thus providing three thicknesses of leather in the rib and affording very substantial additional strength to resist tearing out of the sewing stitches.

Further objects and advantages of the invention will be pointed out in the following more detailed description and by reference to the accompanying drawing, wherein:

Fig. 1 is a perspective view showing the underside of an insole prepared in accordance with usual methods and in readiness for the performance of the first novel step involved in the present invention;

Fig. 1a is a fragmentary section through an insole blank illustrating certain of the earlier steps in the production of the insole;

Fig. 2 is a view similar to Fig. 1 but illustrating the step of reducing the thickness of the feather;

Fig. 2^a is a fragmentary section illustrating the operation of thinning the feather in accordance with the present invention;

Fig. 2^b is a fragmentary elevation showing the cutters used in thinning the feather;

Fig. 3 is a view similar to Fig. 1 but showing the insole as completed in accordance with the present invention;

Fig. 3^a is a fragmentary section illustrating the step of turning down the flap resulting from thinning the feather;

Fig. 4 is a fragmentary section on a line 4—4 of Fig. 1;

Fig. 5 is a fragmentary section on the line 5—5 of Fig. 2;

Fig. 6 is a fragmentary section showing the completed insole with the upper and welt assembled and stitched to the sewing rib; and

Fig. 7 is a fragmentary view similar to Fig. 1^a illustrating a modified procedure.

Referring to the drawing the numeral 1 designates the body portion of an insole or insole blank, which for convenience in description but without limitation, may be considered as an insole or blank of leather (of customary stiffness and thickness such as is usual in Goodyear welt-shoes) having the grain or upper surface 2 and the flesh or lower surface 3. When the terms "grain" and "flesh" are hereinafter employed it is to be understood that they are to be construed broadly as referring to the upper and under surfaces respectively of the insole whatever its material, whether leather, or any combination of leather with other materials, or substitutes for leather.

Following the customary procedure in making a welt insole, the blank 1 is provided with an incision 4 (Fig. 1^a) extending inwardly from its outer edge 5 and with a channeling incision 6 in its flesh surface, said incisions defining the outer flap 7 and inner flap 8 which are integrally joined to the body of the insole and which both consist of portions of the flesh side of the insole, such flaps hereinafter being referred to as "flesh flaps." The incision 4 also defines the feather 9 which is the marginal portion of the grain side of the original blank. Customarily the incision 4 is of such depth that the width of the feather 9 is substantially greater than the thickness of the body of the blank.

Following customary procedure, the flesh flaps 7 and 8 are bent downwardly about their junctions with the body of the insole so that their flesh surfaces substantially contact and the flaps are united by suitable adhesive. Customarily, a reinforcement 10 (Figs. 3, 4 and 5) of canvas or the like is applied to the flesh surface of the insole and a portion of this reinforcement is extended up into contact with the inner flap 8 and cemented to the latter, the flaps 7 and 8 with the reinforcement commonly constituting the sewing rib to which the upper and welt are united by the inseam stitches. While this rib is referred to as a "sewing" rib, it is to be understood that other means than stitches may be used for attaching the upper and welt, for example staples. Customarily, this rib R (Fig. 4) extends from a point 11 (Fig. 1) in the plane of the heel breast around the shank, forepart, and toe of the insole and to a point 12 at the opposite side of the sole, also substantially at the plane of the heel breast.

The description thus far applies to the preparation of a stiff shape retaining ribbed insole substantially in accordance with customary prior

practice and the insole with its rib thus formed is hereinafter referred to as an "embryo" insole since it forms a stage product in the preparation of the improved insole of the present invention.

5 In accordance with this invention, this embryo insole as illustrated in Figs. 1 and 4, is now subjected to an operation or operations whereby the thickness of the feather 9 is substantially reduced so as to make it very flexible. In accordance with 10 the preferred procedure, this operation is performed by the use of the Economy Channeling Machine supplied by the United Shoe Machinery Corporation but somewhat modified by the employment of cutters of novel character. Thus, as 15 illustrated in Fig. 2, there is shown a portion P of the presser foot carrier of such a machine upon which are mounted the two cutters 14 and 15 (Figs. 2, 2^a and 2^b). The operation of thinning the feather is preferably commenced at a point 20 adjacent to the forward end of the shank of the insole at one side and extends progressively around the margin of the insole to a corresponding point at the opposite side of the insole. During this progressive skiving operation, the cutters 25 14 and 15 shave a shaving 16 (Fig. 2) from the flesh or underside of the feather 9, thus reducing the thickness of the feather so that it becomes merely a thin flexible flap 9^a, as shown in Fig. 5. Having thinned the feather in this way and converted it into a flexible flap which forms a continuation of the grain or upper side of the insole and which possesses the high tensile strength of the grain surface of the sole, this flap is then turned downwardly as illustrated in Fig. 3, forming 30 a smooth bend at 17, the flap 9^a extending across the thickness of the insole proper and having its free margin disposed against the outer surface of the rib flap 7. This flap 9^a is now cemented or otherwise firmly secured to the flap 40 7 so that the flap 9^a becomes a constituent part of the complete sewing rib.

The sewing rib is thus substantially stronger than the usual rib since, as above noted, the flap 9^a consists of the strongest and most durable portion of the leather, that is to say the grain portion, and thus substantial strength and more secure anchorage for the sewing stitches is provided.

In thus converting the feather into a flexible flap and making said flap a part of the sewing rib the feather, as such, is eliminated, the foot-supporting surface of the inner sole terminating substantially at the point 17 (Fig. 3^a). When the upper U and the welt W (Fig. 6) are sewed to the rib by means of inseam stitches S, the upper is no longer required to make a sharp S-bend in passing about the edge of the insole, but as illustrated in Fig. 6, extends upwardly in a smooth curve with but slight change in direction from its point of attachment to the sewing rib past the edge of the insole. Thus during the wear of the shoe there is no feather to be bent upwardly by the stress imposed by the upper, and the foot-supporting surface of the insole remains smooth and level and the upper does not become slackened by reason of the upward turning of a feather as is common in welt shoes made by usual methods.

70 While the above-described method of providing the third flap 9^a forming an element of the rib is preferred, it is contemplated that similar results might be obtained in other ways, for instance as illustrated in Fig. 7, by simultaneously forming the channel 6 in the insole blank and a slot 18 75 extending inwardly from the edge 5 of the blank,

thus at one and the same time providing the flesh flaps 7^x and 8^x and the grain flap 9^x , the slot 18 being of such width that the flaps 7^x and 9^x do not exceed in thickness one-third the thickness of the body of the sole, it being understood that after these flaps have thus been formed they may be turned down and united to form the sewing rib substantially as above described.

While certain desirable embodiments of the invention have been illustrated by way of example, it is to be understood that the invention is not necessarily limited to these precise embodiments but is to be regarded as broadly inclusive of any and all modifications and equivalents falling within the terms of the appended claims.

I claim:

1. A Goodyear welt-type insole of a customary thickness and stiffness such that its entire margin can not readily be bent to constitute a sewing rib, said insole having a marginal sewing rib comprising three associated flaps each integral with the body of the insole, and means uniting the flaps to form the rib.

2. A Goodyear welt-type insole of a customary thickness and stiffness such that its entire margin can not readily be bent to constitute a sewing rib, said insole having a sewing rib at its underside, said rib comprising three associated flaps each integral with the body of the insole, and means uniting the flaps to form the rib, the insole being devoid of any marginal feather.

3. A welt-type insole having a marginal sewing rib comprising two flesh flaps and a grain flap, each integral with the body of the sole, and means uniting said flaps, the insole being devoid of any marginal feather.

4. A leather insole having a marginal sewing rib comprising three flaps each integral with the body of the insole, two of said flaps being flesh flaps and the third being a grain flap, the several flaps being bent at their junctions with the body of the insole and contacting one another and means uniting the several flaps to form a sewing rib, the insole being devoid of any marginal feather.

5. A Goodyear welt-type insole having a sewing rib formed of upstanding flaps, the insole having an integral flap of a width greater than the thickness of the body of the insole and of a thickness less than one-half that of the body of the insole and forming a smooth continuation of the upper surface of the insole, said flap being bent downwardly and its free marginal portion constituting an element of the sewing rib.

6. Method of making a welt-type sole which comprises as steps channeling an insole blank in

substantially the usual manner to provide a pair of flesh flaps and a feather, removing material from the flesh side of the feather thereby to decrease the thickness of the latter and reduce it to the form of a flexible grain flap, and turning the several flaps downwardly and uniting them to form a sewing rib.

7. Method of making a welt-type insole which comprises as steps removing material from the

10 mid-portion of the edge of an insole blank so as to provide two flaps each integral with the body of the insole blank, one of said flaps being a flesh flap and the other a grain flap, the two flaps being spaced apart at their junction with the body of the insole, turning said flaps downwardly and uniting them to form constituent elements of a sewing rib.

8. Method of making a welt-type insole which comprises as steps providing an embryo insole having a marginal rib and marginal feather, decreasing the thickness of the feather to make it flexible, and turning the remainder of the feather downwardly into contact with the rib and uniting it to the latter thereby increasing the thickness of the rib and eliminating the feather.

9. Method of making a welt-type insole which comprises as steps providing an embryo insole having a marginal rib and marginal feather, skiving material from the under surface of the feather thereby to decrease its thickness and reduce it to the form of a flexible flap, turning said flexible flap downwardly into contact with the rib, and uniting the flap to the rib thereby to increase the thickness of the rib.

10. Method of making a welt-type insole which comprises as steps providing an embryo insole having a marginal rib and marginal feather, decreasing the thickness of the feather around the forepart and toe portions of the insole thereby to reduce the feather at said portions of the insole to a thin flexible flap, and turning said flap downwardly and attaching it to the rib.

11. Method of making a welt-type insole which comprises as steps providing an embryo insole having a marginal rib and marginal feather, decreasing the thickness of the feather by skiving material from its underside, such decrease in thickness extending from the forward part of the shank at one side of the insole around the forepart and toe to the forward part of the shank at the opposite side of the insole, and turning the thinned portion of the feather downwardly and uniting its free margin to the other components of the rib.

ROBERT H. FESLER.
